United States Patent Office.

FRED. J. MEYERS, OF COVINGTON, KENTUCKY.

Design No. 4,168, dated June 21, 1870.

DESIGN FOR DOG-MUZZLE.

The Schedule referred to in these Letters Patent and making part of the same.

I, FRED. J. MEYERS, of Covington, in the county of Kenton and State of Kentucky, have invented and produced a new and original Design for a Dog-Muzzle, of which the following is a specification.

The accompanying photographic representation, making part of this specification, illustrates my invention.

It consists of a wire muzzle of the form represented, having a front strap, two side straps, and a rear strap,

extending to and appropriately connected with a neck strap or collar.

Claim.

I claim as my invention—

The design for dog-muzzle herein described and represented.
